Specification for Design.

Patented Dec. 26, 1916.

Application filed September 29, 1916. Serial No. 122,945. Term of patent 7 years.

To all whom it may concern:

Be it known that I, JOHN C. FORSTER, a citizen of the United States, and residing at Pittsburgh, in the county of Allegheny and State of Pennsylvania, have invented a certain new, original, and ornamental Design for a Culinary Implement, of which the following is a specification, reference being had to the drawings forming a part thereof, wherein—

Figure 1 is a perspective view of the im-

plement of ornamental design, and Fig. 2 is a similar view with the implement inverted from the position shown in Fig. 1.

I claim:—

The ornamental design for a culinary implement substantially as shown.
